UNITED STATES PATENT OFFICE.

HERMANN SCHMIDT, OF REINICKENDORF-OST, NEAR BERLIN, GERMANY, ASSIGNOR
TO ERNST PAUL LEHMANN, OF BRANDENBURG-ON-THE-HAVAL, GERMANY.

SPINNING TOP.

Application filed January 21, 1928, Serial No. 248,434, and in Germany February 26, 1927.

The invention relates to spinning tops of the type in which from the central axis of the rotating body a spindle with a right-hand thread protrudes on one side and a spindle 5 with a left-hand thread protrudes on the other side. Such tops are spun by applying and quickly removing two nuts.

According to the invention a plate is provided upon at least one of the nuts, the top 10 spinning upon it immediately the two nuts are removed. By means of this plate the top after being spun can be thrown up into the air and caught, so that the game of spinning can be converted into a game of skill. 15 Furthermore, the nuts may be provided on two levers which are pivotally connected together and which spread out when the top is spun. In this case, one of the levers carries the plate. 20 The levers may be connected together by resilient means such as a spring, which, after the nuts have been spread out automatically, re-closes them. Such a spinning device may, if required, be used without the plate. 25 Finally, the nuts may have separate handles and a plate may be provided on each of the nuts so as to enable the top to be thrown from one plate to the other while the top is still spinning. 30 Several forms of spinning top according to the invention are illustrated by way of example in the accompanying drawings, in which:

Figure 1 shows one form partly in elevation and partly in longitudinal section.

Figure 2 is a plan corresponding to Figure 1.

Figure 3 is a second form, shown in section.

Figure 4 is a plan corresponding to Figure 3.

Figure 5 is an elevation of the form according to Figure 3 showing the nuts and plates removed from the top, while

Figure 6 is a plan of one nut and plate.

Figure 7 is a cross-section of a concave spinning plate, and

Figure 8 is a cross-section through a spinning plate having a rim.

In the form of the invention according to Figures 1 and 2, two levers *a* and *b* are pivoted together at *d* by means of the part *c* which projects from the lever *b*. The two ends of the tension spring *f* engage in the lugs *e*, *e*₁ the spring drawing together the

two left hand ends, as seen in the drawing. These ends are provided with angular holes *g*, *g*₁, in which engage, or are guided, the parts *h*, *h*₁ of the twisted spindle of the top *i*. One end of the twisted spindle is made 60 with a right-hand thread, while the other end is provided with a left-hand thread. The ends of the levers *a*, *b*, form, with their holes, the nuts for the twisted spindle.

A circular plate *k* is carried by the end of the lever *b* which end, for example, fits in a sleeve *l* on the plate *k* so that the plate can be detached if desired. The sleeve is flattened where it is connected to the plate *k*, and at this position has a hole *m*.

The holes *g* and *m* coincide, but one of them may be slightly larger than the other to avoid the possibility of the parts not correctly fitting in mass production. In Figure 1 of the drawings the plate *k* is shown flat, 75 but it may be concave as in the form shown in Figure 7, or be provided with a rim or border, as in the form shown in Figure 8. Further, it need not be circular—it may be of any other shape desired.

To spin the top the right hand ends of the levers *a* and *b* as seen in Figures 1 and 2, are held in one hand and are pressed together so as to cause the other ends of the levers to move apart. The top is then inserted between the ends thus opened out so as to bring the ends of the parts *h*, *h*₁ of the twisted spindle respectively over and under the angular holes *g*₁, *g* and *m*.

The levers *a* and *b* are then released, and 90 the spring *f* draws their left hand ends towards each other. This screws both ends of the twisted spindle into the holes in the nuts. The several parts are then in the position illustrated in Figure 1.

If the right hand ends of the levers *a* and *b* are now pressed together smartly, the nuts very quickly move apart, the plate *k* being held down on the lever *b*. This action sets the top spinning rapidly, and when the part 100 *h* of the spindle of the top has emerged from the holes *g*, *m*, the top will move onto the plate *k*, if the device be held at the correct angle, and the top can be thrown into the air and then caught on the plate.

The spinning top may be allowed to glide off the plate onto the floor and received back again on the plate, the plate being jerked forward under the top as it is spinning. Finally, two persons facing each other and each pro-

vided with one of the devices or a suitable plate, may pitch the top to and fro.

In the form illustrated in Figures 3 to 5, handles n and o are fixed to the plates k_1 and k_2 respectively. Each of these plates has an angular hole p_1 p respectively, so that handles and plates together act as nuts for the parts h_1 h of the twisted spindle of the top i . In this construction the top is caused to spin by placing the nuts on the spindle and rapidly removing the upper nut.

The top will then spin upon the under-plate k_2 and it can be thrown up and caught by the same or a second person by means of the plate k_1 .

The concave plate k_2 Figure 7 and the plate k_2 provided with a rim Figure 8 each has a similar handle o fixed to it.

I claim:—

1. A spinning top and means for spinning the same comprising a rotary body having a twisted spindle one part of which projects from each side of said body, the said projecting parts of said spindle having threads of opposite hand, nuts for engagement with said projecting parts of the spindle and a plate on one of said nuts and surrounding the hole therein for the purpose of receiving said top when it spins after removal of the nuts from the spindle.

2. A spinning top and means for spinning the same comprising a rotary body having a twisted spindle one part of which projects from each side of said body, the said projecting parts of said spindle having threads of opposite hand, nuts for engagement with said projecting parts of the spindle and a

plate on one of said nuts and surrounding the hole therein for the purpose of receiving said top when it spins after removal of the nuts from the spindle, and means connected to said nuts adapted to be held in the hands for the purposes, hereinbefore set forth.

3. A spinning top and means for spinning the same comprising a rotary body having a twisted spindle one part of which projects from each side of said body, the said projecting parts of said spindle having threads of opposite hand, nuts for engagement with said projecting parts of the spindle and a plate on one of said nuts and surrounding the hole therein for the purpose of receiving said top when it spins after removal of the nuts from the spindle, and means connected to said nuts adapted to be held in the hands, said means comprising levers pivotally connected together and adapted to be operated by the hands, so that the nuts can be moved apart by said levers to spin the top.

4. A spinning top and means for spinning the same as claimed in claim 3, including a sleeve on the nut which is provided with the plate, said sleeve fitting on one of the levers, substantially as hereinbefore set forth.

5. A spinning top and means for spinning the same as claimed in claim 3, including resilient means connecting the two levers for the purpose of automatically drawing the nuts together after they have been moved apart.

In testimony whereof I affix my signature.

HERMANN SCHMIDT.
